UNITED STATES PATENT OFFICE.

THOMAS J. LEE, OF MINNEAPOLIS, MINNESOTA.

DEVICE FOR REMOVING ICE FROM RAILROAD-RAILS.

1,205,757.

Specification of Letters Patent. Patented Nov. 21, 1916.

Application filed January 3, 1916. Serial No. 69,896.

To all whom it may concern:

Be it known that I, THOMAS J. LEE, citizen of the United States, resident of Minneapolis, county of Hennepin, State of Minnesota, have invented certain new and useful Improvements in Devices for Removing Ice from Railroad-Rails, of which the following is a specification.

The object of my invention is to provide 10 an attachment for a locomotive by means of which an accumulation of ice on the railroad rails can be easily and quickly removed.

A further object is to provide a device which will be under the immediate control 15 of the engineer in the cab and may be made operative or inoperative at will.

The invention consists generally in various constructions and combinations, all as hereinafter described and particularly 20 pointed out in the claim.

In the accompanying drawings forming part of this specification, Figure 1 is a side elevation of the forward portion of a locomotive, showing my invention applied thereto, Fig. 2 is a detail view, showing the position of the device with respect to the forward trucks of the locomotive, Fig. 3 is a detail sectional view of one of the nozzles, Fig. 4 is a sectional view on the line $x-x$ 25 30 of Fig. 3.

In the drawing, 2 represents a locomotive of ordinary construction, having forward trucks 3 and cow-catcher 4.

5 is a pipe running back to the boiler 35 through the cab, where suitable means is provided within control of the engineer for regulating the admission of steam thereto. At the forward end of the pipe 5 is a coupling 6 and from this coupling pipes 7 extend downwardly to a point in front of the 40 trucks and in the rear of the cow-catcher and are supported on the cow-catcher by suitable means, such as brackets 8. Each of these pipes is provided with a nipple 9

in which a nozzle 10 is mounted. This nozzle has an opening 11 therein with gradually converging walls terminating in an outlet orifice 12 that is comparatively small in cross sectional area. This orifice is located near the top of the track rail 13 and should the engineer see ice on the rails which would interfere with the operation of the locomotive, he can turn on the steam, which, being discharged through the nozzles 10, will very quickly melt the ice which may have formed on the rail head and the engine will pass over the point where the ice has been melted before it has had time to form again.

It will be noted that the nozzles are arranged at an angle to the rail heads and the jets of steam will be directed down upon these heads in such a way that the ice will be rapidly and thoroughly melted.

I claim as my invention:

The combination, with a locomotive, of a steam supply pipe arranged beneath and connected with the boiler for taking live steam therefrom, said pipe being centrally arranged substantially with respect to the 70 boiler and having couplings at its forward end in advance of the locomotive driving wheels, of tubes radiating outwardly and downwardly from said couplings to a position in the rear of the cow-catcher and in 75 front of the forward trucks, and nozzles mounted on the lower ends of said tubes and having tapered passages therein terminating in substantially circular, restricted outlet openings and supported above and 80 adjacent to the track rails, said nozzles directing the steam vertically upon the heads of the rails and having means for bracing said nozzles on the locomotive frame.

In witness whereof I have hereunto set 85 my hand this 27th day of December, 1915.

THOMAS J. LEE.

T. J. LEE.

DEVICE FOR REMOVING ICE FROM RAILROAD RAILS.

APPLICATION FILED JAN. 3, 1916.
